RADIO RECEIVER

Edward F. Andrews, Chicago, Ill.

Application October 27, 1932, Serial No. 639,821

15 Claims. (Cl. 250—27)

This invention relates to radio receivers and has for its principal object to provide a receiver energized by direct current and including an interrupter to render said current transformable and provided with means for preventing high frequency energy from the interrupter from being impressed to an objectionable extent upon the amplifying tubes.

A further object of the invention is to provide a receiver of this type in which the interrupter, amplifying tubes and the means for isolating the undesired frequency are located in compact relation within a single housing.

Other objects, advantages and capabilities of the invention will appear from the following description of a preferred embodiment thereof, taken in conjunction with the accompanying drawings, in which—

Figure 1 is a diagram of a radio receiver embodying my invention;

Fig. 2 is a diagram of the alternating current cable and switch plug for the receiver;

Fig. 3 is a diagram of the direct current cable and switch plug for this receiver;

Fig. 4 is a diagram showing the energy supply part of a modified receiver;

Fig. 5 is a diagram of a direct current cable and switch plug used in the embodiment of the invention illustrated in Fig. 4;

Fig. 6 is a sectional view through the receiver;

Fig. 7 is a plan view thereof with the cover removed;

Fig. 8 is an elevational view of the receiver, the casing being shown in section;

Fig. 9 is a diagram showing the energy supply part of a further modified receiver.

Fig. 10 is a diagram of a direct current cable and switch plug used in the embodiment of the invention illustrated in Fig. 9, and

Fig. 11 is a diagram of an alternating current cable and switch plug for this receiver.

Referring to the drawings, the reference numeral 10 designates the antenna while the tubes of the set are designated 11, 12, 13 and 14. The speaker cone is designated 15 and the field coil and the voice coil by the reference numerals 16 and 17, respectively. It will readily be understood from the following description that many novel and valuable features of the invention may be utilized in sets having different circuits and that it is not intended to limit the invention to a set of the wiring system shown. The particular set herein selected for the purpose of illustrating the invention is a simple four tube superheterodyne, the tube 11 being the first detector

and oscillator, tube 12 the intermediate frequency amplifier, tube 13 the second detector, and tube 14 the audiofrequency power amplifying tube.

The transformer 18 and rectifying tube 19 are provided for supplying plate current of appropriate voltage for the operation of the set. The plate of the rectifier 19 is connected to winding 20 of transformer 18. This transformer comprises two other windings 21 and 22.

A group 37, Fig. 1, of contacts 23, 24, 30, 31, 34, 28 and 36 is mounted on the receiver and is adapted to cooperate with either of the switch plugs 42 and 65 hereinafter described. One end of winding 22 of transformer 18 is connected to contact 23. The other end of winding 22 is connected to a magnetically operated interrupter 17 and to contact 29 of a double pole double throw switch 26. Interrupter 17 comprises a magnet, excited by a coil 79, and contacts 80 one of which is stationary and the other carried by a vibrating armature. The connection from winding 22 to the interrupter 17 is completed through coil 79 and contacts 80 to pole 25 of switch 26. Condenser 82 is connected across coil 79 and contacts 80 to prevent arcing at the contacts and to minimize interference resulting from the operation of the interrupter. This interference is further reduced by means of a metallic casing 78 completely shielding the interrupter and connected to the chassis of the set. This casing is preferably lined with sound insulating material. A relatively high resistance 81 may be inserted across the points 80 to reduce the voltage built up across the points.

One end of winding 21 of transformer 18 connects to contact 24. The other end of winding 21 is connected to a second pole 32 of the double pole double throw switch 26. Contact 33 of the switch is connected to contact 30 and contact 35 is connected to contact 31 and one end of winding 20 of the transformer.

The other end of winding 20 connects to plate 46 of a rectifier tube 19. Contact 34 connects to one end of the speaker field coil 16 through a radio frequency choke coil 54. The other end of field coil 16 connects to the common ground of the chassis. Contact 36 also connects to the chassis. One end of the filaments of tubes 11, 12, 13 and 14 and rectifier tube 19 is grounded to the chassis. The other ends of the filaments are connected together and to pole 25 of switch 26 by means of conductor 86.

For operation of the set on alternating current a cable 38, Fig. 2, is provided. This cable consists of two conductors 40 and 41 connected at 55

one end to the prongs of a plug 39 adapted to plug into a conventional outlet box. The other end of cable 38 carries a switch plug 42 having a plurality of contacts, designated 47, 48, 49, 50, 51, 52 and 53, corresponding to the contacts 24, 30, 31, 34, 28, 23 and 36 of group 37 and adapted to be engaged with them respectively when the switch plug 42 is applied to said group. Conductors 40 and 41 are connected to contacts 47 and 48, respectively, of switch plug 42. Contacts 49 and 50 are connected together by a conductor 43 while contacts 52 and 53 are connected together by conductor 44. Contact 51 is left open.

With switch plug 42 engaged with the contacts of group 37 and switch 26 thrown with its poles in the up position, as viewed in Fig. 1, the set is connected for alternating current operation. Winding 21 acts as the primary and connects to the prongs of plug 39 through switch pole 32, switch contact 33, contacts 24 and 30 of group 37, contacts 47 and 48 of switch plug 42 and conductors 40 and 41 in cable 38.

Winding 22 supplies current to the filaments of tubes 11, 12, 13, and 14 and rectifier tube 19, one end of the filaments being connected by means of conductor 86, switch pole 25, and switch contact 29 to one end of winding 22. The other ends of the filaments are grounded to the chassis and the other end of the winding 22 is likewise grounded to the chassis through contact 23, contact 52, conductor 44, contact 53 and contact 36.

In this condition of switching, the winding 20 of transformer 18 acts as the secondary. One end of winding 20 connects to contact 31 and switch contact 35. The circuit continues from contact 31 through contact 49, conductor 43 and contact 50 of switch plug 42 and through contact 34, choke coil 54 and speaker field coil 16 to chassis ground. The other end of winding 20 is connected to plate 46 of rectifier tube 19.

Resistors 55 and 56 are connected across the speaker field coil 16 to utilize part of the voltage drop across the speaker field coil as grid bias voltage, which is applied to output tube 14. Cathode 57 of rectifier tube 19 connects through radio frequency choke coil 58 and through the various coupling devices to the plates of the tubes to supply the plate voltage. Resistor 59 reduces this voltage to a suitable value to be applied to the screens of the various tubes while resistor 61 further reduces this voltage to the required value to obtain grid bias for tube 12. Variable resistor 60 is the volume control.

The rectified output of rectifier 19 is suitably filtered by condensers 62 and speaker field coil 16 which acts as a choke coil. The tuning of the set is accomplished by means of variable condensers 88 and 89 which may be operated by a common shaft. Increased sensitivity may be obtained by introducing a small amount of regeneration in the second detector tube 13. This is accomplished by means of a small tickler coil 64 connected in the plate circuit of tube 13 and inductively coupled to the grid circuit of this tube.

In order to adapt the set for use with direct current, as for example from an automobile storage battery, the switch plug 42 is removed and replaced by a switch plug 65, Fig. 3. This switch plug consists of a plurality of contacts designated 66 to 72 inclusive, and corresponding to the prongs of plug 37. Contacts 66 and 69 of switch plug 65 are connected together by conductor 73. Contacts 67 and 68 are left open. A two-conductor shielded cable 87 connects the switch plug 65 to the battery 83. Conductor 74 of the cable

87 connects at one end to contact 70 of switch plug 65 and, at the other end, to the positive pole of the battery 83. Conductor 75 of the cable 87 connects at one end to contact 71 of switch plug 65 and, at the other end, to the negative pole of battery 83. Contact 72 of switch plug 65 connects to one end of the metallic shield 76 around the cable. The other end of this shield connects to the negative pole of the battery 83 and acts as a third conductor of the cable.

When the switch plug 65 is engaged with the contacts of group 37 and switch poles 25 and 32 are in the down position, as viewed in Fig. 1, the set is connected for direct current operation. In this case winding 22 acts as the primary of transformer 18. One end of winding 22 is connected to the negative pole of the battery 83 through contact 23 of group 37, contact 71 of switch plug 65 and conductor 75 in cable 87. The other end of winding 22, or a suitable tap thereof, as suggested at 45 in dotted lines on Fig. 1, is connected to the positive pole of the battery through coil 79 and contacts 80 of interrupter 77, pole 25 and switch contact 27 of switch 26, contact 28 of group 37, contact 70 of switch plug 65, and conductor 74 in cable 87.

When so connected the interrupter 77 will operate to interrupt the current through the circuit and supply a pulsating current to the winding 22 which produces an alternating current of 30 higher voltage in windings 20 and 21 of the transformer. One end of winding 20 is connected to plate 46 of rectifier tube 19. The other end of winding 20 is connected to one end of winding 21 by means of pole 32 and switch contact 35 of 35 switch 26. The other end of winding 21 connects to contact 24 of group 37, contacts 66 and 69 of switch plug 65 by means of conductor 73 and from contact 34 of group 37 to speaker field coil 16. In this manner windings 20 and 21 are 40 connected in series to act as the secondary of transformer 18. The plate 46 of the rectifier tube is by-passed to contact 34 by a condenser 85. The condenser 85 being in shunt with windings 20 and 21 prevents the voltage in these windings 45 from attaining an excessive value during that part of the cycle when no current is passing through the rectifier. This condenser should be capable of withstanding high voltages and should be of the proper capacity for efficiency and proper 50 functioning of the interrupter contacts.

The filament current to the tubes is supplied by the battery through conductor 74 and shield 76 of cable 87. The positive pole of battery 83 is connected through conductor 74, contact 70 of switch plug 65, contact 28 of group 37, switch contact 27 and pole 25 of switch 26, and conductor 86 to the filaments of the tubes. The negative pole of battery 83 is connected through shield 76 of cable 87, contact 72 of switch plug 65, and contact 36 of group 37 which is connected to the chassis.

It will be seen that the circuit from the positive pole of battery 83 through conductor 74, contact 70, contact 28, switch contact 27, and switch pole 25 is common to both the filament circuit and the interrupted primary circuit whereas the negative side of the filament circuit is completed to battery 83 by means of metallic shield 76 of cable 87 and the primary circuit is made through conductor 75 of cable 87. It has been found that when a common circuit is used from the battery to the set, to furnish both filament and primary current, an objectional interference is sometimes created due to the coupling of the filament 75

circuit to the interrupter circuit through the common battery conductors. When the interference from this source is of sufficient intensity to be objectionable it may be overcome as shown in Fig. 3 by using two separate leads 75 and 76 for the negative side of the battery circuit and by making conductor 74, contact 10, contact 28, switch contact 27 and switch pole 25 of sufficiently low resistance to minimize the coupling between the two circuits. If further reduction of this coupling be required completely separate circuits may be employed.

The interrupter 77 is preferably constructed in a unit separate from the set and equipped with a plug adapted to engage in a socket on the chassis of the receiver. The shield case 78 of the vibrator is preferably lined with sound absorbing material to reduce the audible sound of the interrupter when in operation.

It will be seen that switch 26 serves as the on and off switch for the set. When the switch plug 42 is engaged with the set and the poles of switch 26 are in the up position, as viewed in Fig. 1, the set is on, and when the poles of switch 26 are in the down position the set is off. When switch plug 65 is engaged with the group of contacts 37 the set is off when poles of switch 26 are in the up position, as viewed in Fig. 1, and on when the poles are in the down position. Switch 26, in conjunction with conductor 73 in switch plug 65 and conductors 43 and 44 in switch plug 42, serves to complete the circuits for operation of the set on either alternating or direct current. The circuit arrangement, Fig. 1, is such that the set may be operated on alternating current with interrupter 77 removed from the set.

It will appear that if desired this change over could be performed by plugs alone or switch alone by a suitable multiplication of contacts. It is, however, preferred to provide the contacts of group 37 in the form of prongs mounted on the edge of the base of the set, the switch plugs 42 and 65 being plugs provided with contacts in the form of sockets adapted to receive said prongs.

Fig. 4 illustrates the transformer circuit of a modified embodiment of the invention. In this modification a double pole single throw switch 63 is used and the interrupter is not incorporated in the set.

The group 112 of contacts, in the set, consists of seven contacts designated 88 to 94 inclusive. One end of winding 22 of transformer 18 is connected to contact 93. The other end of winding 22 connects to contact 92 through pole 95 and switch contact 96 of switch 63. A conductor 86 connects to switch pole 95 to furnish filament current to the tubes, the filament circuit being completed as shown in Fig. 1. One end of winding 21 connects to contact 88. The other end of winding 21 is connected to contact 89 through switch contact 98 and pole 97 of switch 63. One end of winding 20 connects to plate 46 of rectifier tube 19. The other end of winding 20 is connected to contact 90. Contact 94 is grounded to the chassis.

Cable 38, Fig. 2, is used with this embodiment of the invention for operation of the set on alternating current. When switch plug 42 is engaged with the contacts of group 112 and the poles of switch 63 are in the down position, as viewed in Fig. 4, the set is in operation. Winding 21 of transformer 18 acts as the primary. The connection is made by conductors 40 and 41 in cable 38, contacts 47 and 48 of switch plug 42 to contacts 88 and 89. Contact 88 connects to one

end of winding 21. The other end of winding 21 is connected to contact 89 through switch contact 98 and pole 97 of switch 63.

Winding 22 serves to furnish the filament current for the tubes. One end of winding 22 is connected to the filaments of the tubes by means of conductor 86. The other end of winding 22 connects to contact 93. The circuit is then completed through contact 52, conductor 44, and contact 53, in switch plug 42, to contact 94 which is grounded to the chassis of the set. Winding 20 acts as the secondary, one end of this winding 20 being connected to plate 46 of rectifier tube 19, and the other end connecting to contact 90. From contact 90 the circuit is completed through contact 49, conductor 43 and contact 50 of switch plug 42 to contact 91. Contact 91 connects to radio frequency choke coil 54 and then to speaker field 16 as shown in Fig. 1.

For operation of this modified set on direct current a cable 84, Fig. 5, is provided. This cable consists of two conductors 99 and 100 and a metallic shield 101 around the two conductors. An interrupter 77, similar to that shown in Fig. 1, is connected in series with conductor 100 in cable 84. A switch plug 111 is carried by one end of the cable. The other end of the cable connects to a battery 83. The positive pole of battery 83 is connected to contact 106 of switch plug 111 by means of conductor 99. Contact 108 is connected to the negative pole of battery 83 by means of the metallic shield 101 around the cable. Contact 107 of switch plug 111 also connects to the negative pole of battery 83 through conductor 100, and coil 79 and contacts 80 of interrupter 77. Contacts 102 and 105 of switch plug 111 are connected by a conductor 109 while contacts 103 and 104 are connected by a conductor 110.

With switch plug 111 in engagement with contacts of group 112 and switch 63 with its poles in the lower position, as viewed in Fig. 4, the circuit is complete for direct current operation. In this case the winding 22 serves as the primary of transformer 18. One end of winding 22 connects to contact 93 of group 112 through contact 107 of switch plug 111, conductor 100 in cable 84, coil 79 and contacts 80 of interrupter 77 to the negative pole of battery 83. The other end of winding 22 connects through pole 95 and contact 96 of switch 63, contact 92, contact 106 of switch plug 111 and conductor 99 of cable 84 to the positive pole of battery 83. This circuit also supplies current to the filaments of the tube in the set by means of conductor 86. The circuit to the grounded ends of the filaments is made from the chassis through contact 94, contact 108 of switch plug 111 and through the metallic shield 101 of cable 84 to the negative pole of the battery 83. The interrupter 77 is completely enclosed in a shield case 78 and a resistance 81 and a condenser 82 is provided as previously described in connection with Fig. 1. Shield case 78 is connected to shield 101 of cable 84.

Windings 20 and 21 are connected in series to form the secondary of transformer 18. One end of winding 20 connects to plate 46 of rectifier tube 19. The other end of winding 20 connects to one end of winding 21 through contact 90, contact 104, conductor 110 and contact 103 of switch plug 111, contact 89, contact 98 and pole 97 of switch 63. The other end of winding 21 connects by means of contact 88, contact 102, conductor 109 and contact 105 of switch plug 111, and contact 91 to speaker field coil 16 as in Fig. 1.

It will be seen that, in this embodiment of the

invention, when poles of switch 63 are in the lower position, as viewed in Fig. 4, the set is on for either alternating current or direct current operation and with the poles of switch 63 in the upper position the set is off in both cases. This permits the switch to be mounted on and operated by the volume control 60.

When the set is being operated on direct current, winding 22 of transformer 18 is the primary while windings 20 and 21 are connected in series to form the secondary. When the set is operated on alternating current, winding 21 acts as the primary, winding 20 as the secondary and winding 22 supplies filament current. Windings 20, 21 and 22 together with other circuit values may be so proportioned that the voltages throughout the set are substantially similar whether the set is operated on direct or alternating current. In this manner all the windings of the transformer are used in either case, permitting of compact and economical design.

In Figs. 6, 7 and 8 a physical embodiment of the invention is illustrated. The set comprises a base 113 which is preferably circular and in the form of an inverted dish. The underside of this base accommodates the wiring and various small parts such as resistors and by-pass condensers. A loud speaker 114, preferably of the cone type, is mounted in the center of the base with the apex of the cone pointed towards the base. Suitable spacers may be employed between the field pot 115 and the base 113 of the set, if necessary to bring the rim 116 of the speaker cone to a suitable height to accommodate the tubes and other apparatus mounted on the base therebelow.

The component parts of the radio set such as the tubes 11, 12, 13, 14 and 19, transformer 18, condensers 88 and 89, filter condensers 62, and optionally the interrupter 77 are mounted on the base in the space available around the speaker field pot. The tubes and their associated coupling transformers are mounted at the periphery of the base with their axes perpendicular to the base.

A decorative cover 117, adapted to be supported by rim 116 of speaker 114, is placed over the set. The cover may be fastened to rim 116 by a number of screws 118 having decorative heads. The top surface of cover 117 directly over the speaker cone is perforated to permit egress of sound from the speaker cone. The cover 117 extends downwardly to a point somewhat above the lower edge of base 113. The diameter of the cover 117 at this point is somewhat greater than the diameter of the base 113 so as to provide an annular opening 119 to permit egress of sound waves from the underside of speaker. In this manner the cover 117 forms an effective baffle for the speaker. Shaft 122 for operating condensers 88 and 89 and volume control shaft 121 project above the top of the cover 117. Knobs 126 are carried by shafts 121 and 122 and are adapted to be easily removed. Thus it will be seen that to obtain access to the set for replacement of tubes or adjustment the screws 118 and knobs 126 are removed and cover 117 lifted off the set. A rotating scale 123, preferably of frusto-conical shape is carried by the shaft controlling condensers 88 and 89. The portion of cover 117 adjacent to scale 123 is formed as at 125 and an opening 124 provided for convenient observation of the scale by the operator.

The contacts of the group 37 are mounted on base 113 in definite order and the contacts of the

switch plugs 42 and 65 are correspondingly arranged for proper engagement therewith. The contacts of the group 37 may suitably be in the form of prongs while the contacts of the switch plugs may suitably be sockets provided in said plugs.

In the modification of the invention shown in Figs. 9, 10, and 11, the tubes 11, 12, 13, 14 and 19 are similar to those of the same numbers in the previously described modifications. The transformer 18 is substantially similar and comprises the windings 20, 21 and 22. The interrupter 77 is substantially similar and its stationary contact 80 is grounded. The other end of the winding 79, that is the end remote from the vibrating contact 80 is connected to one end of the winding 22. The other end of the winding 22 is connected to a contact 127 and to a conductor 128 which serves to supply current to the filaments of all the tubes 11, 12, 13, 14 and 19. The other ends of the filaments are grounded. The contact 127 is adapted to be connected to a contact 129 by means of a switch pole 130, when in its uppermost position, as viewed in Fig. 9.

In this modification the receiver is provided with a group 131 of contacts which are analogous to group 37 and group 112 of the previously described modifications. The group 131 comprises contacts 132, 133, 134, 135, 136, 137 and 138. Contact 129 is connected to contact 132. Contact 133 is connected to a contact 139 which is adapted to be connected to a contact 140 by the pole 130 when in its lower position, as viewed in Fig. 9. The contact 140 is shown connected to a suitable tap of winding 21, although it may be connected to the upper end thereof if desired, other steps being taken to attain the necessary correlation between the windings 20, 21 and 22. Contact 134 is connected to the upper end of the winding 21. The other end of the winding 21 is connected to contact 136. Contact 135 is connected to one end of the winding 20. The other end of the winding 20 is connected to the plate of the tube 19. Contact 137 is connected to the field coil 16 of the speaker 15 in substantially the same manner as described heretofore. Contact 138 is grounded.

In order to adapt the set for use with direct current supplied by a battery 141, a switch plug 142 is employed having contacts 143, 144, 145, 146, 147, 148 and 149 corresponding to contacts 132, 133, 134, 135, 136, 137, and 138 respectively, these contacts being engaged in the order stated. Contact 147 is connected to contact 148. Contact 145 is connected to contact 146. Contact 143 is connected by a conductor 150 to the positive plate of the battery 141. Contact 149 is connected to the negative plate of the battery 141 by means of a shielding coating 151 provided around the conductor 150. When the switch plug 142 is connected to the group 131 of contacts, the negative plate of the battery 141 is grounded through the shield 151 and contacts 149 and 138. Contact 144 being left open, contacts 133 and 138 are disconnected and the off position of switch 130 is its lower position, as viewed in Fig. 9. The positive plate of the battery 141 is connected through contacts 143, 132 and 128, the switch pole 130 (in its upper position), and contact 127 to the winding 22 and the conductor 128.

The current passing through the winding 79 actuates the interrupter 77 as described before, and winding 22 serves as the primary for the transformer 18. Windings 20 and 21 are connected in series through contact 135, contact 146, 78

contact 145 and contact 134. When employed with alternating current, switch plug 152, shown in Fig 11, is employed. This plug comprises a series of contacts 153, 154, 155, 156, 157, 158 and 159, corresponding respectively to contacts 132, 133, 134, 135, 136, 137 and 138 of the group 131. Of these contacts 153, 155 and 159 are left open corresponding to the isolation of contacts 132, 134 and 138. Contacts 154 and 157 are connected to the prongs of the plug 160 which may be inserted in any suitable power outlet supplying alternating current. Contacts 156 and 158 are connected. When the switch plug 152 is applied to the group 131, contacts 154 and 157 communicate to contacts 133 and 136 so that the winding 21, or the lower portion thereof, is energized when the switch pole 130 is moved to its lower position as viewed in Fig. 9, this being the on position for the alternating current hook-up. When the switch pole 130 is moved to its upper position, the set is off. Contact 153 is isolated and winding 22 serves as a secondary, supplying filament current to the conductor 128. This current passes through the filaments to ground and also passes through winding 79 and contact 80 to ground. This current is, however, relatively slight and does not affect the vibrator 77. Winding 20 is connected through contacts 135, 156, 158, 137, and thus to the field coil in the manner previously referred to.

An important result obtained by this modification is that the production of radio frequency disturbances by the vibrator 77 is reduced to a minimum, particularly owing to the manner in which the interrupter is directly grounded. In order further to reduce interferences it is preferred to provide choke coils 161 and 162 in the line 128. It will be noted that coil 162 is provided between tubes 12 and 13 and that coil 161 is located on the output side of tube 14. The inductances of the choke coils 161, 162 are correlated to the resistances of the filaments to prevent voltage disturbances from passing along the conductor 128 in the output-to-input direction. The choke coils 161, 162 combine with the filaments to provide a filter circuit containing inductances and resistances. Filtering action is greatest at the filaments of the tubes 11 and 12, which is important since disturbances in these tubes are capable of greater amplification in the final output.

Other important effects obtained by this modification are its great simplicity, considering the results attained, and the fact that the switch employed may be of simple and heavy construction while taking up a very small amount of space.

Although the invention has been disclosed in connection with the specific details of preferred embodiments thereof, it must be understood that such details are not intended to be limitative of the invention except in so far as set forth in the accompanying claims.

Having thus described my invention, what I claim as new and desire to secure by Letters Patent of the United States is:

1. In a radio receiver, in combination, thermionic tubes having filaments and plates, a transformer adapted to be energized from a source of alternating current or from a source of direct current, a conductor conveying current to said filaments, said filaments being arranged in parallel, an interrupter adapted continuously to interrupt the direct current supplied to the transformer, and choke coils in series in said conductor between said filaments through which coils

said filaments are connected to said source of direct current when the set is operated by direct current, for the purpose of preventing the amplification through said tubes of electrical disturbances created by said circuit interrupting means. 5

2. In a radio receiver, in combination, thermionic tubes having filaments and plates, a transformer adapted to be energized from a source of direct current, an interrupter adapted continuously to interrupt the direct current supplied to the transformer, a conductor supplying current to said filaments which are arranged in parallel, and a plurality of choke coils in series in said conductor at least one of said choke coils being between said filaments for the purpose of preventing the amplification through said tubes of electrical disturbances created by said circuit interrupting means. 10

3. In a radio receiver, in combination, thermionic tubes having filaments and plates, a transformer adapted to be energized from a low voltage storage battery, an interrupter adapted continuously to interrupt the direct current supplied to the transformer, said transformer having a secondary adapted to supply high voltage current 20 for said plates, a conductor supplying current to said filaments which are arranged in parallel, and a plurality of choke coils in series in said conductor at least one of said coils being between said filaments from said interrupter and preventing the amplification of electrical disturbances from the interrupter in said tubes, said tubes, interrupter and transformer being mounted close together in a compact unit. 30

4. In a radio receiver, a series of tubes connected in cascade progressively to amplify a signal from input to output of said series, said tubes having filaments with one end grounded, a source of filament current containing an undesired high frequency component, having one side grounded, 35 a conductor connecting the ungrounded ends of the filaments together, a high frequency choke coil in said conductor between the input and output end of said series, a second conductor connected to the first conductor at the output 40 end of said series of tubes and with the ungrounded side of said source of filament current, and a choke coil in the second conductor, said choke coils having impedances so proportioned to the resistances of the filaments to constitute 45 therewith an effective filter progressively attenuating the undesired component towards the input end of said series. 50

5. In a radio receiver, a series of tubes connected in cascade progressively to amplify a signal from input to output of said series, said tubes having filaments with one end grounded, a source of filament current, a continuous interrupter giving an undesired high frequency component to said filament current, said source and interrupter having one side grounded, a conductor connecting the ungrounded ends of the filaments together and connecting the filaments to the ungrounded side of the source of filament current, and a choke coil in said conductor having an impedance proportioned to the resistances of the filaments to constitute therewith an effective filter attenuating the undesired high frequency, said tubes and interrupter being located in compact relation within the receiver. 55

6. In combination, a battery having one side grounded, and a battery operated radio receiver comprising a series of tubes connected in cascade progressively to amplify a signal from input to output of said series, said tubes having filaments 60

with one end grounded, a continuous circuit interrupter having one side grounded, the other being connected to the ungrounded side of the battery, a conductor connected to the ungrounded 5 ends of the filaments and connecting the filament at the output end of the series to the ungrounded side of the battery, and choke coils in said conductor correlated with the resistances of the filaments to constitute an effective filter for 10 objectionable high frequency energy produced by said interrupter, attenuating said high frequency energy progressively from the output to the input end of the series, said tubes and interrupter being located in compact relation within 15 said receiver.

7. A battery operated radio receiver comprising a base, a loud speaker, thermionic tubes, other radio apparatus and a current interrupter, a housing cooperating with said base to enclose the 20 speaker, thermionic tubes, other radio apparatus and the interrupter in compact relation, said thermionic tubes having filaments energized from the battery which supplies current to the interrupter, and a choke coil in the circuit between 25 said interrupter and said filaments.

8. A battery operated radio receiver comprising a housing, thermionic tubes, other radio apparatus and a current interrupter all located in compact relation within said housing, said thermionic tubes having filaments energized from the battery which supplies current to the interrupter, and a choke coil in the circuit between said interrupter and said filaments.

9. In a battery operated radio receiver, in combination, a plurality of thermionic tubes having plates and filaments, a step-up transformer having a primary winding and a secondary winding, a rectifier connected to the second winding for supplying high voltage to said plates, vibrating means supplying pulsating low voltage direct current to the primary winding, a low resistance, high frequency choke coil, and other receiving apparatus, a metal support carrying the aforesaid devices and a common housing enclosing them, a low voltage battery external to said housing for supplying current to said filaments and to said vibrating means, one terminal of said battery being connected to one side of said filaments and one side of said vibrating means and 40 primary winding circuit, and conductor means connecting the other terminal of said battery to the other side of said filaments and the other side of said vibrating means and primary winding circuit, said choke coil being connected in 45 series with said conductor means between said filaments and said vibrating means and primary winding circuit for attenuating the high frequency current produced by said vibrating means in the filament circuit.

10. In a battery operated radio receiver, in combination, a plurality of thermionic tubes having plates and filaments, a step-up transformer having a primary winding and a secondary winding, a rectifier connected to the secondary winding, 45 for supplying high voltage to said plates, vibrating means supplying pulsating low voltage direct current to the primary winding, a plurality of low resistance, high frequency choke coils, and other receiving apparatus, a metal support carrying the aforesaid devices and a common housing enclosing them, and a low voltage battery external to said housing for supplying current to said filaments and to said vibrating means, one terminal of said battery being connected to one side of said filaments and 50

one side of said vibrating means and primary winding circuit, the other terminal of said battery being connected to the other side of said filaments and the other side of said vibrating means and primary circuit, said choke coils being connected between the input tube of said receiver and said vibrating means and primary circuit for attenuating the high frequency current produced by said vibrating means in the filament circuit.

11. In a radio receiver, in combination, a battery, a metal base to which one side of said battery is grounded, a plurality of thermionic tubes mounted on said base and having plates and filaments, said filaments being grounded to said base, a continuous current circuit interrupter mounted on said base and having one side connected to said grounded side of the battery, a transformer mounted on said base and having a winding in the interrupter circuit, a rectifier deriving energy from said transformer and delivering high voltage direct current to said plates, conductor means between the ungrounded side of the battery and the ungrounded side of the interrupter circuit and the ungrounded side of the 25 filaments, and a choke coil in said ungrounded conductor means between the interrupter and the filaments.

12. In a radio receiver, in combination, a battery, a plurality of thermionic tubes having plates and filaments, a continuous circuit interrupter, a transformer having a winding in the interrupter circuit, a rectifier deriving energy from said transformer and delivering high voltage direct current to said plates, a common ground 30 to which one terminal of the battery, one side of each filament and one side of the interrupter circuit are grounded, conductor means between the ungrounded side of the battery, the ungrounded side of the interrupter circuit and the ungrounded side of the filaments, and a choke coil in said conductor means between the interrupter and the filaments.

13. In a radio receiver, in combination, a battery, a metal base, a plurality of thermionic tubes having plates and filaments mounted on said base, a continuous circuit interrupter mounted on said base, a transformer mounted on said base and having a winding in the interrupter circuit, a rectifier deriving energy from said transformer and delivering high voltage direct current to said plates, and a choke coil, said thermionic devices, interrupter, transformer, rectifier and choke coil being arranged in compact relation, a housing enclosing them, said battery, filaments and interrupter circuit being grounded to said metal base, conductor means between the ungrounded side of the battery, the ungrounded side of the interrupter circuit, and the ungrounded sides of the filaments, said choke coil being connected in said ungrounded conductor means between the interrupter and the filaments.

14. In a radio receiver, a series of tubes connected in cascade progressively to amplify a signal from input to output of said series, said tubes having filaments, a source of filament current, a continuous circuit interrupter giving an undesired high frequency component to said filament current, conductor means connecting one end of each filament together and connecting the filaments to the source of filament current, and a choke coil in said conductor means having an impedance proportioned to the resistances of 75

the filaments to constitute therewith an effective filter attenuating the undesired high frequency, said tubes and interrupter being located in compact relation within the receiver.

15. In combination, a battery and a battery operated radio receiver comprising a series of tubes connected in cascade progressively to amplify a signal from input to output of said series, said tubes having filaments, a continuous circuit interrupter connected to the battery, conductor means connected to one end of each fila-

ment and connecting the filaments to the battery, and at least two choke coils in said conductor means correlated with the resistances of the filaments to constitute an effective filter for objectionable high frequency energy produced by said interrupter, attenuating said high frequency energy progressively from the output to the input end of the series, said tubes and interrupter being located in compact relation within said receiver. 5 10
